RAYMOND J. FARRELL AND FAY A. ARDRON, OF SEATTLE, WASHINGTON.

SPARK-PLUG.

1,139,654.

Specification of Letters Patent.

Patented May 18, 1915.

Application filed May 23, 1914. Serial No. 840,419.

To all whom it may concern:

Be it known that we, RAYMOND J. FARRELL and FAY A. ARDRON, citizens of the United States, residing at Seattle, in the county of King and State of Washington, have invented certain new and useful Improvements in Spark-Plugs, of which the following is a specification.

This invention relates to improvements in spark-plugs for explosive engines; and its object is the improvement in such devices to render the same more efficient, durable and less liable to short-circuit by safeguarding the porcelain sleeve against breakage.

With these ends in view, the invention consists in the novel construction, adaptation and combination of parts, as will be hereinafter described and claimed.

20 In the accompanying drawings, Figure 1 is a longitudinal section of our improved spark-plug in its preferred form. Fig. 2 is a side elevation of the same; and Fig. 3 is an underside end view thereof.

25 In carrying out the invention, we provide a shell 5, preferably of steel, having at its lower end an external screw-thread 6 for engaging in a threaded hole provided in an engine-cylinder. Said shell is bored from 30 the top to afford a chamber 7 which terminates at an annular shoulder 8 and below the latter is an extension 9 having a contracted lower end which terminates at the mouth 10. At its upper end the chamber 35 7 is screw-threaded, as at 11.

The shell 5 constitutes the outer electrode of the plug and the inner electrode is formed of a rod 12 which is screw-threaded at the top and at its lower end is provided with a 40 relatively large head 13. The latter is formed substantially rectangular in horizontal section and is further characterized by having slots 14 and 14¹ extend diametrically therethrough to furnish a plurality of 45 prongs 15 which may be spread apart to regulate the spaces or gaps between the outer corners 16 of the electrode-head and the opposing rim 17 of the other electrode.

As customary in spark plugs, the inner 50 electrode or rod 12 extends axially through a sleeve 18 of porcelain, or an equivalent insulating material. In this instance, the sleeve 18 extends through a tubular casing 19 which is desirably made of brass, although any other suitable metal may be used 55 instead. Said casing is formed with a body

of a diameter to fit in the chamber part 9 and through the bore of a securing nut 20 which engages the screw-threads 11. The casing 19 is furthermore provided with a 60 peripheral ridge 21 adapted to fit within the chamber 7.

22 and 23 represent washers of a yielding material, such as asbestos, which are interposed between the ridge 21 and the shoulder 8 and nut 20, respectively. Another washer 24 of similar material is employed between the lower end of the casing 19 and a collar 18¹ formed integral with the sleeve 18 at its lower end. A washer 25 of similar 70 character is likewise utilized between the electrode-head 13 and the sleeve 18, said head and the associated washer being advantageously accommodated in a recess 19¹ provided in the sleeve whereby lateral movement of the head 13 is prevented. 75

The sleeve 18 is of a length to extend above the casing 19 and surrounding the protruding end of the sleeve is a ring 26 of an insulating material, such as asbestos, and 80 a washer 27 surmounts the sleeve as shown in Fig. 1. The external diameters of the ring 26 and washer 27 are, by preference, equal to the corresponding diameter of the casing 19. Fitted over the washer 27 and 85 extending down below the interstice between the ring 26 and the casing is a cap 28 of a tough insulating material such as conventionally known as fiber. This cap not only serves to prevent the admission of moisture 90 through the referred to interstice, but also serves to protect the asbestos elements 26 and 27 from being destroyed by being abraded or knocked off when struck by a wrench or other article. 95

29 represents a metal washer which serves as a seat for a clamping nut 30 which engages the screw-threads of the rod 12.

31 is a binding nut for connecting a circuit wire to the rod. 100

According to the present invention, the porcelain sleeve 18 is inclosed by a metal casing 19 and the cap 28 thereby obviating any danger from water coming in contact with the sleeve to cause the same to break 105 when hot. Furthermore, the casing 19 being formed of a material having a high conductivity for heat, will not cause the sleeve to become unduly hot when operating. The insulation afforded by the porcelain sleeve and the elements 26 and 27 is such that there is no danger of short-cir-

cuiting of the current and particularly as the referred to elements are prevented by the cap 28 from absorbing moisture.

To clean the electrodes, or for regulating their relative positions, the plug is removed as a whole from the cylinder with which it is employed, whereupon the inner electrode, or rod, 12 is adjusted by means of the clamping nut 30, the washer 25 ordinarily 10 accommodating itself to the changed position of the head or where the adjustment is considerable, a new washer of suitable thickness may be substituted for the one in use.

15 What we claim, is—

1. In a spark-plug of the class described, the combination with a shell forming one electrode, a rod forming the other electrode of the device, of an insulating sleeve surrounding said rod, a metal casing surrounding said sleeve and extending from within said shell to a short distance below the top of the sleeve, means coöperating with said rod for securing the latter to the sleeve and 20 also serving to secure the sleeve to the casing, means for securing the casing to the shell, and a cap overlapping the upper end of the casing serving as a cover for the upper ends of the sleeve and casing to close 25 the interstice between the same.
2. In a spark-plug of the class described, the combination with a shell forming one electrode, and a rod forming the other electrode of the device, of an insulating sleeve surrounding said rod, a metal casing sur- 30 35

rounding said sleeve and extending from within said shell to a short distance below the top of the sleeve, means coöperating with said rod for securing the latter to the sleeve and also serving to secure the sleeve 40 to the casing, means for securing the casing to the shell, and a cap overlapping the upper end of the casing serving as a cover for the upper ends of the sleeve and casing to close the interstices between the same. 45

3. In a spark-plug of the class described, a shell constituting one electrode, a screw-threaded rod having an enlarged head and serving for the other electrode, a porcelain sleeve inclosing said rod and provided at 50 one end with a recess to accommodate the head thereof, a metal casing inclosing said sleeve and extending into said shell, a nut engaging a screw-thread provided in the shell for coupling the casing to the latter, 55 means superposed on said casing for insulating the sleeve with respect to said rod, a cap provided to cover such insulating means and likewise the interstice between said means and the casing, and a clamping 60 nut engaging the screw-threads of the rod for securing the same within the sleeve.

Signed at Seattle, Wash., this 18th day of May, 1914.

RAYMOND J. FARRELL.
FAY A. ARDRON.
